UNITED STATES PATENT OFFICE.

HERMAN E. S. CHAYES AND AUGUST P. JURGENSEN, OF NEW YORK, N. Y., ASSIGNEES
TO CHAYES DENTAL INSTRUMENT CORPORATION, OF NEW YORK, N. Y., A COR-
PORATION OF DELAWARE.

QUADRANGLE

Application filed February 21, 1925. Serial No. 10,775.

This invention relates to a holding device for dental tools.

A general object of the invention is to provide a supplemental or extension drill holder adapted to be mounted on a dental drill head or hand piece and to press the drill or other tool at an angle to the axis of the main hand piece in order to facilitate the application of the drill to the work. A further object is to provide improved means for holding the drill in position in the chuck. Still another object is to so design the drill holding device as to obstruct as little as possible the operator's view of the work.

With these and other objects in view the invention includes an elongated drill holder extension member arranged to hold a drill at substantially right angles to its axis and in a terminal portion thereof. A spring-pressed member mounted on the elongated holder is adapted to be moved along the holder to thereby cause a forked locking member to move into and out of engagement with a circumferential groove formed in the stem or shaft of the dental tool.

The invention also includes a formation or design of the parts which does away with projecting portions and protuberances which might interfere with or obstruct a clear view of the work being performed by the tool.

Other features of the invention will be hereinafter referred to.

In the drawings, in which a preferred embodiment of the invention has been selected for illustration,

Figure 1 is a view in side elevation of an extension drill holder embodying the invention.

Figure 2 is a view in longitudinal section of the device shown in Figure 1.

Figure 3 is a perspective view in disassembled relation of a dental tool and a locking device used in connection therewith.

Figure 4 is a plan view of a portion of the device shown in Figure 1.

Referring to the drawings for a more detailed description of the invention, an extension drill holder is shown in which a hollow shell portion 10 provided with a knurled hand gripping portion 11 is adapted to be fitted over the end of a dental drill head or hand piece. Within the shell 10 an operating shaft 12 is adapted to be received in the chuck of the main drill holder in order to transmit

power from the main drill holder to the extension member mounted thereon. A jointed connection 13 between the shell 10 and a main frame member 14 provides for the arrangement of the part 14 at any one of four different angles with relation to the axis of the shell portion 10. Within the jointed connection 13 a universal connection 15 provides for the transmission of power from the shaft 12 to a shaft 16 journaled in the member 14. The forward end of the member 16 is provided with a bevel pinion 17 meshing with a corresponding bevel pinion 18 formed on a chuck 19 which receives the stem or shaft 20 of the tool 21 being used. The chuck 19 is journaled in the forward portion 22 of the section 14 and extends substantially at right angles to the axis of the driving shaft 16.

In order to hold the tool stem 20 in its seat in the chuck 19 a sleeve 23 is slidably mounted on the extension member 14 and is provided at its forward end with a forked member 24 adapted to engage with a groove 25 formed in the stem 20 of the tool near the upper extremity thereof. The sleeve 23 is normally pressed into its forward or locking position shown in Figure 2 by the action of a coil spring 26 placed between the rearmost extremity of the sleeve 23 and a flange or shoulder 27 formed on the rearward end of the member 14 and included in the joint structure 13.

With this construction it will be seen that the sleeve 23 is pushed forwardly into locking position, the forked member 24 extending into an opening formed for the purpose in the head 22 and intersecting the recess in which the upper end of the tool stem 20 projects to thereby engage in the groove 25 in the stem and lock the stem in place within the chuck. In order to release the tool from its position within the chuck 19 the sleeve 23 is readily moved rearwardly under the pressure of a thumb or finger of the operator whereupon the forked member 24 is withdrawn from its locking position and the tool 100 is free to drop from its position in the chuck 19.

Another feature of the invention resides in the shape or formation of the forward portion of the extension drill holder. In order to cause the device to present as little obstruction to the view of the operator as possible, the forward portion of the sleeve 23 merges

into contact with the head or forward extremity 22 through an inclined or tapering formation shown at 28 in the drawing. With this formation the position and operation of the tool held in the head 22 can be closely observed for the reason that no obstructions or protuberances extend from the side wall of the extension drill holder to interfere with a full view of the operation.

10 In addition to the advantages obtained in the improved lock and general design described, an impervious surface is presented throughout the extent of the forward portions of the device which include tight and close joints which function to exclude the entrance of moisture into the position of the operating parts. This feature is an important one in the operation of devices of this general character as will be clear.

15 20 What is claimed is:—

In a dental tool holder, an elongated body portion having a drive shaft journaled there-

in, an enlarged head member at one end of the body portion, a tool-holding chuck journaled in the head member and extending substantially at right angles to the axis of the body portion, the head member being provided with an opening in its rearward face, a longitudinally movable sleeve member enclosing said body portion and provided with a forked locking device at its forward extremity, said locking device entering said opening to engage and lock a tool in said chuck, a flange at the rear extremity of the body portion, and a spring enclosing the body portion between said flange and the rearmost extremity of said sleeve, said spring acting normally to press the sleeve forwardly into locking position.

25 30 35 In testimony whereof we affix our signatures.

HERMAN E. S. CHAYES.
AUGUST P. JURGENSEN.
